DRILL PIPE RETRIEVER FOR WELL
DERRICKS

Odell Sanders, Kermit, Tex.

Application February 5, 1945, Serial No. 576,262

10 Claims.

(CL 214—1)

1

This invention relates to well drilling derricks and it has particular reference to drill pipe retrievers and methods for such derricks.

In drilling wells, especially deep oil wells, the derrick must of necessity be of considerable height. Workmen are required to be stationed in the upper part of the derrick to manipulate pipe elevators for handling drill pipe. It sometimes happens that the pipe will escape the grasp of a workman on the "monkey board" of the derrick and will fall against the opposite side of the derrick, out of reach of the operator and the latter, to retrieve the pipe must release his safety belt and at great risk, work his way around the derrick to the opposite side and, aided by a line, maneuvers the pipe into a more convenient position for handling.

It is a principal object of the present invention to provide apparatus to facilitate the work of retrieving pipe displaced in the manner described and at the same time reduce materially the hazard attending such an operation. Moreover, time being an important factor in drilling wells, the invention contributes much towards conserving time otherwise consumed in recovering displaced pipe.

Another object of the invention is to provide a simple but highly effective pipe handling apparatus consisting of a barrel and a plunger, provided with a suitable head, reciprocable therein on a plane at right angles to the pipe rising in the derrick and actuatable by a line extending downwardly and about the cathead on the draw-works line shaft and countered by a weight suspended under the derrick floor by a second line connected to the plunger. Operation is effected by the driller or attendant at the direction of the pipe handler in the derrick and the plunger, carrying pipe retaining means advances the displaced pipe towards the handler.

The invention embraces also a pipe centering arc or rack which orients the dislodged pipe for engagement by the retaining means of the plunger.

With the foregoing objects as paramount, the invention has further reference to certain features of accomplishment which will become apparent as the description proceeds, taken in connection with the accompanying drawings wherein:

Figure 1 is a plan view of a preferred form of apparatus constructed according to the invention, shown installed in the upper portion of a well derrick, the latter being in transverse sec-

tion.

Figure 2 is a perspective view of the barrel and plunger per se.

Figure 3 is a plan view of the barrel and plunger, showing the barrel in longitudinal section, and

Figure 4 is a view in transverse section, taken on line 4—4 on Figure 3.

Continuing with a more detailed description of

2

the drawing, reference is primarily made to Figure 1 wherein numeral 10 denotes the legs of a conventional steel derrick, truncated at a point below the top and on a plane with the platform 11, generally called the "monkey board." The platform 11 is affixed securely to the braces 12 of the derrick and extends towards the center of the latter in order that an operator standing on the platform may be in a convenient position to manipulate an elevator or the pipe rising from the floor of the derrick, far below.

Extending from one side of the derrick to the other in front of the platform 11 is an arcuate member 14. This member may be constructed of any suitable material but it is shown as consisting of a pipe, having flattened ends 15, bolted to reinforced frame-work of the derrick. The pipe 14, which may be aptly termed an arcuate pipe centering device, is so located intermediate the center of the derrick and the wall thereof opposite the platform 11, that it will catch a pipe 16 escaping the elevator or workman and the shape of the member will cause the pipe to come to rest at a position immediately in front of the operator on the platform 11. The dotted lines in Figure 1 purport to show different positions of the pipe escaping the elevator. It is apparent that regardless of the direction of displacement, the pipe will be caught and centered by the member 14. Suitable braces such as rods 17 are provided to reinforce the members 14. Not only is the active pipe caught and centered when displaced as described but also any stands or sections racked in the derrick may be oriented by the member 14 for convenient handling when displaced.

After being properly located by the centering device 14, it is necessary to move the pipe into operative position for convenient application of the elevator by the operator on platform 11. This is accomplished by the device better shown in Figures 2, 3 and 4. This device consists of a tubular body or barrel 18 which is rigidly fixed by any suitable means, such as a bracket 19 to the frame of the derrick in transverse relation to the wall of the derrick opposite the platform 11. In this position, the inner end of the barrel will be in alignment with the vertical axis of the pipe 16 centered in the derrick. Any form of reinforcing means, such as braces 20, may be employed to rigidify the barrel 18.

Slidably disposed in the barrel 18 is a plunger 21 which may also be of tubular stock and affixed to this plunger adjacent its rearmost end are diametrically opposed eyes 22. These eyes extend through longitudinal slots 23 in each side of the barrel 18 and besides providing binding points for wire lines 24 and 25, these eyes limit the travel of the plunger in view of the fact that the ends of the slots 23 afford stops therefor at each limit

of travel, and also secure the plunger and head against rotation.

Near the rearmost end of the barrel 18 is affixed as by welding, a boss 26. On this boss is mounted a pin 27 serving as an axis for a sheave 28. Near the opposite end of the barrel 18 and on each side thereof, similar bosses 26 are affixed as mountings for sheaves 29 and 30.

The wire line 24 is affixed at one end to an eye 22 and extends over sheave 28 and towards the opposite end of the barrel to extend over sheave 29, thence downwardly and through the floor 31 of the derrick and a weight 32 is affixed to the end of the line under the floor 31. It is obvious then that the weight 32, in the absence of any counter force, will maintain the plunger 21 in the retracted position shown in the figures.

Acting counter to the force exerted by the weight 32 is that applied on the wire line 25, which latter is fastened to the opposite eye 22 and extends over sheave 30, thence downward to and is wound upon a cat-head, not shown, on the draw-works line shaft, which latter is conventional equipment on the derrick floor.

Mounted on the inner end of the plunger 21 is a U-shaped head 33 and, by virtue of the function of member 14 in centering the displaced pipe, combined with the relative position of the plunger, the pipe retainer or head 33 engages the pipe and upon actuation of the plunger 21, under direction of the operator on the platform 11 to an operator on the derrick floor, the displaced pipe is moved to a position more accessible to the operator on platform 11, as indicated by the broken lines in Figure 1.

It is obvious that while the member 14 is shown and described as being U-shaped or arcuate, satisfactory results may be secured by constructing this member so that it will be angular or otherwise, so long as it will be effective to direct falling pipe to a predetermined point for reception by the retaining head 33 of the plunger 21. Moreover, in some if not all cases, provision may be made on the head 33 to prevent pipe from becoming accidentally displaced therefrom. This may consist of confronting projections 33a on the legs of the substantially U-shaped head, as shown in Figures 2 and 3 but omitted in the showing in Figure 1.

Inasmuch as the foregoing description of construction embraces also the independent and joint function of parts, a further description of operation is rendered unnecessary.

Manifestly, the construction as shown and described is capable of some modification and such modification as may be construed to fall within the scope and meaning of the appended claims is also considered to be within the spirit and intent of the invention.

What is claimed is:

1. The method of handling sections of pipe in a well derrick, which includes the steps of orienting the upper end of the pipe to a point on the opposite side of the well bore from the monkey board and on a line operably extending through the monkey board and the vertical axis of the well bore, then moving the upper end of the pipe along said line by means positioned on the opposite side of the well bore from the monkey board for engagement with or disengagement from elevating devices.

2. The method of handling sections of pipe in a well derrick, which includes the steps of orienting the upper end of the pipe to a point on the opposite side of the well bore from the monkey

board and on a line operably extending through the monkey board and the vertical axis of the well bore, then moving the upper end of the pipe along said line by means positioned on the opposite side of the well bore from the monkey board for engagement with or disengagement from elevating devices, and remotely controlling the moving means.

3. In a well derrick having a monkey board and having means for raising and lowering pipe in the well bore; means for orienting a stand of pipe to a point within the derrick at the side opposite from the monkey board; and means disposed at said point of orientation for moving the upper end of the pipe stand along a line from the point of orientation toward and from the monkey board.

4. In a derrick as set forth in claim 3, means for preventing axial rotation of said pipe moving means.

5. In a derrick as set forth in claim 3, said moving means being horizontally reciprocable; and means for preventing axial rotation of said pipe moving means.

6. In a derrick as set forth in claim 3, said moving means being horizontally reciprocable and including a stationary member and a movable member, one of said members having a slot and the other a projection engaging the slot, and means for reciprocating the movable member.

7. In a derrick as set forth in claim 3, said moving means being horizontally reciprocable and including a stationary barrel having slots in each side thereof, a plunger reciprocably mounted in the barrel, members on the plunger extending through said slots, and means engaging the members for reciprocating the plunger.

8. In a derrick as set forth in claim 3, said moving means being horizontally reciprocable and including a stationary barrel having slots in each side thereof, sheaves mounted on said barrel, a plunger reciprocably mounted in the barrel, members on the plunger extending through said slots, a weight supporting cable attached to one of said members and extending over a sheave on one side of said barrel, and a second cable attached to the opposite member and extending over sheaves on the opposite side of said barrel for operating said plunger.

9. In a derrick as set forth in claim 3, means operable remotely from the monkey board for actuating the pipe moving means.

10. In a well derrick having a monkey board and having means for raising and lowering pipe in the well bore; means for orienting a stand of pipe to a point within the derrick at the side opposite from the monkey board; and means disposed at said point of orientation for moving the upper end of the pipe stand along a line from the point of orientation over the well bore toward and from the monkey board.
